FRANCE

PROCESS FOR TREATING HYDROCARBON OILS

Application filed February 29, 1932, Serial No. 595,927, and in France September 23, 1930.

This invention relates to processes for treating oils and other liquids, particularly for mixing hydrocarbon, vegetable or other oils with acid or other reagents and to products derived therefrom. An apparatus which may be employed to carry out this process is also described but not claimed herein. Claims for this apparatus are contained in a copending application, Ser. No. 595,926 filed February 29, 1932.

10 In current practice in treating oils such as mineral hydrocarbon oils with acid, the oil and acid are agitated and then allowed to separate by gravity. The action between acid and lubricating oils is relatively long 15 when this method is used. Furthermore the treatment is uneconomical, entailing considerable unnecessary loss of oil and acid. In addition it is a batch process and not continuous.

20 The principal object of the present invention is accordingly to provide a simple process of the kind described capable of efficiently treating oils and other liquids with difficultly miscible reagents and especially in the case of 25 mineral hydrocarbon oils, of eliminating at least in part the disadvantages mentioned above; and to produce novel products of the type mentioned.

This application is a continuation in part 30 of our copending application Ser. No. 513,733, filed February 5, 1931. The French application corresponding to Ser. No. 513,733 was filed in France September 23, 1930, this being the earliest filed foreign application 35 corresponding thereto.

The invention comprises the novel products as well as the novel processes and steps of processes according to which such products are manufactured, the specific embodiments of which are described hereinafter by way of example and in accordance with which we now prefer to practice the invention.

Further and more specific objects, features and advantages clearly appear from the detailed description given below. The accompanying drawing which forms a part of this specification, illustrates by way of example an apparatus which may be employed for carrying out an embodiment of the process. 50 Fig. 1 represents a diagrammatic elevation

of a preferred embodiment of the invention. Fig. 2 represents a detail view of one of the oil spray nozzles. Fig. 3 represents a detail view of one of the acid spray nozzles.

Referring now particularly to the drawing, 1 indicates a substantially cylindrical chamber for mixing and settling oil and acid. The oil is introduced through a series of oil atomizers designated as 2, which are circumferentially spaced near the upper edge of the cylinder at about equidistance from one another. Centrally disposed on the top of the chamber 1 is an acid atomizer 3. Atomizers 2 and 3 are located as shown in the outermost heads of drumshaped hoods 4 and 5 respectively, the opposite end of each hood communicating directly with the interior of the chamber 1. The nozzles 2 are of a special type as shown in greater detail in Fig. 2. Each comprises a hollow cylindrical body 2a which is separated from a chamber 2b by means of a diaphragm 2c. The liquid forced through pipe 2e under the effect of pressure can only escape to chamber 2b through a row of slots 2f which are not perpendicular to the axis but tangential. The liquid passing through these slots thus acquires a quick revolving motion, and the combination of this revolving motion within chamber 2b, with the effect of the pressure applied, disperse the jet through opening 2j in form of a cloud or mist of very finely divided droplets.

These nozzles are preferably supplied with oil under pump pressure. The acid nozzle 3 is also of a special type as shown in Fig. 3. It is supplied with acid pumped thereto either with or without air under pressure of approximately 0.1 to 2 kg. per square cm. It comprises the following parts: A hollow cylindrical body 3b terminated by a hollow cone 3e having two openings. Through opening 3a the liquid to be atomized is forced by pressure and 3d is the only outlet which consists in an annular slot limited between the conical button 3c and the edges of the concentrical hollow cone 3e. The width of the annular slot 3d is adjustable with a screw 3f by means of which the button 3c can be set more or less close to the edges of the hollow cone 3e. Another annu-

lar slot 3g terminates concentrical space 3h limited between the hollow cone 3e and the hollow cone 3i. Compressed air introduced through opening 3j escapes through the annular slot 3g at a point where it meets and disperses with violence the liquid discharged through the annular slot 3e.

The nozzles described are capable of atomizing liquids passed therethrough to a fineness of particle size of about 0.005 mm. to 1 mm. in diameter. Nozzles of the type described were thus used in order to obtain the results below, although we believe that a variation in range of particle size produced thereby is permissible. It is preferable that the size of the reacting particles be not so large as to cause loss of oil and acid to vary to any considerable extent from that described below.

20 The nozzles 2 are directed inwardly and downwardly so that their axes projected form the elements of a cone while the center acid spray is along the longitudinal axis of the cone. The dimensions of this cone may 25 be varied but as shown in Fig. 1 the axes meet at about one-third of the height of the chamber 1 from the top thereof. The atomizers 2 and 3 produce in the chamber a mixture of acid and oil fogs. The particles of this fog mixture are so fine that 30 there is almost an immediate contact between all of the acid and all of the oil to form a substantially homogeneous mixture thereof, and as this fog descends in 35 the chamber 1 it tends to settle out and deposit particles of liquid therefrom. This liquid collects in the bottom of the chamber 1 and rises to about the level there shown.

Air is supplied to the nozzle 3 through the 40 line 6 under pressure of approximately 0.5 kg. per square cm., being passed through the air sieve 7 to remove particles which might block the nozzle.

This air passes out of the chamber 1 45 through a pipe 8 leading to an air filter chamber 9 filled with Raschig rings 10 or similar material to prevent the outflow of liquid therewith. The acid supplied to nozzle 3 is driven through an acid line 11 by pump 12. 50 It passes through an acid filter 13 to remove any particles which might clog the nozzle 3.

The oil passes through a pipe line 14 to the nozzles 2 being forced through the line by pump 15. The pumps 12 and 15 are proportionating pumps—that is they may be adjusted to give the right proportion of acid and oil respectively at a given speed of rotation of their common shaft 101. Prior to reaching the pump, the oil may pass through 55 a heat exchanger to carry steam or chilled brine, or other temperature-regulating medium, in order to heat or cool the oil as desired. A control float 18 controls a by-pass valve 19 in a line 20 to by-pass the pump 15. This 60 float member is in a chamber 21 connected by

a pipe 22 with a short well 23 running from the bottom of chamber 1. The liquid rises in the chamber 21 to the same height as in chamber 1 and the float 18 floats on the top of this liquid. It is connected by a suitable means, such as a chain, to an arm operating the valve 19 and in case the level of the liquid becomes too high in chamber 1 and correspondingly in chamber 21, the valve opens so as to allow liquid to pass through the pipe 20 to by-pass the pump and reduce the amount of oil passing to the sprays 2.

From the lower part of the well 23 through pipe line 24 the liquid passes through a pump 25 and to reaction chambers 26 and 27. Pump 25 is connected on the same shaft with pumps 12 and 15, which are set to deliver respectively acid and oil to the sprays in proper proportion and pump 25 being correspondingly set to pump away the acid-oil mixture. Each of the reaction chambers consists of an upright hollow cylinder with a motor 28 in a cap thereon. The lower end of the motor shaft has a gear 29 which meshes with a gear on top of shaft 32, which in turn through gear 30 which meshes with gear 31 operates shaft 33. On both shafts are mounted circular bands 34 and 35 respectively. Rings 34 are mounted at right angle with respect to the rings 35 so that they will not interfere with one another on rotation and will provide sufficient motion to prevent substantial settling of the oil-acid mixture pumped into the reaction chamber. As the shafts are rotating reverse in respect to each other, the tendency which each one of them would have to carry the liquid in a rotating motion, is annihilated by the other one, and any centrifuging effect is thus avoided, which would otherwise tend to throw heavier particles suspended in the liquid against the walls of the chamber. The speed of rotation of these rings 34 and 35 is approximately 200 to 400 R. P. M.

Liquid passes from the reaction chamber 26 to chamber 27 by pipe 36. From reaction chamber 27 it may pass by pipe 37 to a reaction and insolubilizing chamber 38. This chamber is supplied with water through a line 39, being pumped by pump 40. The amount of water is suitably regulated. The chamber 38 is also provided with a motor 28 and gear driven shafts 32 and 33 provided with rings 34 and 35 as in the case of the other reaction chamber.

The mixture passing from the insolubilizing chamber by pipe 41 passes to a centrifugal separator 42 running at high speed about 14000 R. P. M. Acid-refined oil passes out of the pipe 43 and acid-sludges pass out of the pipe 44.

The process which we prefer to carry out in this apparatus is as follows:—Oil (for example a lubricating oil having a viscosity of 400" Saybolt Universal viscosimeter at 100° F.) is heated to 80° F. by the heat ex-

changer 16 and is introduced under pump pressure through the sprays 2 at the rate of about 9 gals. per minute. The sprays deliver a fine smoke or fog into the chamber 1 and are met therein by the fine smoke or fog resulting from the spraying of sulfuric acid, for example 96% H_2SO_4 or other like refining reagent passing from the spray 3. Sulfuric acid of this strength for the treatment of the above oil is preferably passed through the spray at the rate of 0.2 gals. per minute. The fog of the mixed acid and oil descends and settles as a liquid in the bottom of the chamber, the air passing out of the chamber 15 and away from the acid mixture. At this point in the process if a test tube of the mixture of acid and oil be taken, it will show a substantially homogeneous liquid, that is, there will not be any apparent stratification 20 of any sulfuric acid and oil or the presence of insoluble products in suspension detectable by the naked eye.

In the form just mentioned it appears that the sulfuric acid and oil have assumed practically the form of a homogeneous solution and reaction between the materials to produce a sludge containing asphalt, coloring material, etc., should now be allowed to take place. We allow this reaction to take place 30 for the production of these products while substantially preventing the settling out of the insoluble products. This is done by passing the acid or mixture to one or more reaction chambers 26, 27 and 38, through which 35 the liquid slowly passes, occupying a sufficient interval to allow the reaction between sulfuric acid and the products to be removed from the oil to take place. In order to prevent the settling mentioned, the ring agitators are used which continue to rotate and keep the liquid stirred up. For the oil mentioned above, the time of passage through the reaction zone or reaction chambers is approximately 10 minutes. Having passed 40 through the reaction chambers, the material may pass through the insolubilizing reaction chamber 38 in which water is added to it at the rate of approximately 0.06 kg. per minute. This results in the final insolubilization 45 of the asphalt and other products to be separated and the material is now ready to be separated which is done by passing it to a separator having a speed of approximately 14000 R. P. M. As shown the acid oil passes out 50 separately from the asphaltic and other constituents.

The above description has been made in connection with a specific oil run under specific conditions. It is to be understood that 55 the description is illustrative of the process and the process is not confined to the details there given. The strength of the sulfuric acid may vary from 10 to 100% by weight of H_2SO_4 content, or even fuming sulfuric acid may be used. The oils may be of vari-

ous types viz. gasoline, kerosene, transformer oils, spindle oils, neutral oils, machine oils, motor oils, cylinder oils, and the like.

We have obtained successful results with temperatures of the untreated oils ranging as low as 30° F. to as high as 160° F. The period for reaction in the reaction chamber or chambers will vary also according to the type of oil and this may be controlled by the rate of pumping.

Other reagents may be employed such as sulfuric acid and in place of hydrocarbon oils vegetable oils or others to be subjected to reaction with such reagents may be used.

After the reaction between the oil and reagent, it is important that impurities be separated rapidly from the treated oil. For this purpose we employ, as indicated, a separation by centrifuge or we may submit the treated liquid to shock or any other force exercising a rapid separating effect on liquids of different densities, as set forth in copending application Ser. No. 513,733, filed Feb. 5, 1931.

We have found that our process mentioned conserves time and expense, including particularly a marked lowering in oil losses and in amount of acid required. Below is given a table showing the results of tests on various types of oil as compared with the results obtained by employing the old process in which the acid was brought into contact with the oil in two "dumps" with intermediate settling. The acid employed in all of these tests contained 96% H_2SO_4 . The table is as follows:

Original oil	Viscosity	C. T. P. industrial treatment			Conventional industrial treatment			165
		Percent of acid used	Losses of oil	Resulting NPA color	Percent of acid used	Losses of oil	Resulting NPA color	
Transformer oil.	108" S. U. at 100° F. (transformer oil).	9	2.8	1 1/4	12	10	1 1/4	110
Lubricating neutral oil.	200" S.U. at 100° F.	3	5	4 1/4	8	14	4 1/4	115
Lubricating spindle oil.	120" S.U. at 100° F.	3.25	5.6	2 1/4	8	7	3	120
Lubricating neutral oil.	220" S.U. at 100° F.	2	4.5	3 1/4	8	10.5	3 1/4	125
Lubricating neutral oil.	235" S.U. at 100° F.	2 3 4 6 8	5.7 6.2 6.4 7.1 8.5	4 3 1/4 2 1/4 2 1/4 1 1/4	8	10	3 1/4	130
Lubricating machine oil.	300" S.U. at 100° F.	2	5	4 1/4	8	13	4 1/4	
Lubricating machine oil.	400" S.U. at 100° F.	3 4 5 6 7 8	7 7.54 8.84 9.38 10.3 11.2	4 3 1/2 3 2 1/4 2 1/4 2 1/4	8	13	3 1/4	125
Motor oil.	70" S.U. at 212° F.	3	6.2	4 1/2	5.5	12	4 1/2	

Savings on the acid range from 30 to 70% of the consumption as compared with the conventional process. The savings on refined oil range from 20 to 80% of the oils recovered when using the conventional process. The oils obtained are acid oils free from substantially all insoluble particles resulting from the reaction. The acid index of these oils is low and is such that they may be immediately neutralized and decolorized with clay; or even the clay treatment by contact without neutralization may be employed without additional settling. The process is continuous enabling the treatment of large quantities of material in a relatively small time.

As stated above the apparatus which we prefer to employ in carrying out this process is as described above. In practice we find it inexpensive to install and operate and highly efficient in action. It is capable of continuous operation and with its compact form is able to handle large quantities of material in a relatively small space.

Although we have described the feed from the well of the mixing chamber 1 as carried on by a pump and the supply of the water for insolubilization in the insolubilizing machine as also under pressure, it will be noted that the flow of materials through the reaction and insolubilizing chambers and to the separator may be carried on by gravity if desired.

While we have described our improvements in great detail and with respect to certain preferred embodiments thereof, we do not desire to be limited to such details or embodiments since many changes and modifications may be made and the invention embodied in widely different forms without departing from the spirit and scope thereof in its broader aspects. Hence we desire to cover all equivalents and all modifications and forms coming within the language or scope of any one or more of the appended claims.

The term "difficulty miscible liquid reagent" employed in the claims is intended to include chemical reagents normally liquid at room temperature capable of reacting with the hydrocarbon oil to chemically change certain constituents thereof. It includes refining agents such as sulphuric acid, phosphoric acid and other liquid agents well known to those skilled in the art.

What we claim as new and desire to secure by Letters Patent is:—

1. The steps in the process for treating hydrocarbon oil with a difficulty miscible liquid reagent which comprises atomizing said oil and reagent into a space sufficient to permit atomization to form a fog admixture, forming a liquid containing said oil and reagent from said fog, and separating said oil from said reagent to prevent prolonged reaction.
2. A process for treating an oil with a

difficulty miscible liquid reagent which comprises atomizing said oil and said reagent into a space sufficient to permit atomization and to form a fog admixture, settling said fog in said space to form a liquid containing said oil and reagent, retaining the oil and reagent in said space for a predetermined interval and separating the oil from the products of reaction.

3. A process for treating a hydrocarbon oil with acid which comprises atomizing hydrocarbon oil and acid into a space sufficient to permit atomization and to form a substantially homogeneous admixture thereof, settling said oil and acid in said space, withdrawing said oil and acid into a chamber, retaining said oil and acid in said chamber for a predetermined interval and separating the oil from the acid sludge.

4. A process according to claim 3 in which an insolubilizing agent is introduced into the oil and acid mixture prior to the separation of the oil from the acid sludge.

5. A process for refining oils which comprises bringing together a fog of sulfuric acid and a fog of impure hydrocarbon oil, settling a substantially homogeneous liquid mixture therefrom, agitating the liquid while allowing reaction between the sulfuric acid and hydrocarbon oil to occur to avoid substantially settling out of asphaltic coloring material and the like and centrifugally separating the said asphaltic coloring materials and the like from the substantially impure oil.

6. A process according to claim 5 in which water is added during the course of the reaction to produce insolubilization of constituents in the oil.

7. A process according to claim 5 in which the acid employed is concentrated sulfuric acid containing a H_2SO_4 content of above approximately 62%.

8. A process according to claim 5 in which the size of the acid and oil particles is from 0.005 mm. to 1 mm. approximately.

9. A process according to claim 5 in which the oil treated is a mineral petroleum oil fed at the rate of approximately nine gallons per minute in which the acid is sulfuric acid of about 96% and is fed at the rate of about 0.2 gallons per minute and in which the reaction period prior to separation of the substantially pure oil from the other constituents is about 10 minutes.

In testimony whereof we have signed our names to this specification.

JEAN ADOLPHE SCHAEFFER.
GEORGE PFERSCH.

CERTIFICATE OF CORRECTION.

Patent No. 1,908,924.

May 16, 1933.

JEAN ADOLPHE SCHAEFFER, ET AL.

It is hereby certified that the name of the co-inventor in the above numbered patent was erroneously written and printed as "GEORGE PFERSCH" whereas said name should have been written and printed as "GEORGES PFERSCH" as shown by the records of the case; page 1, line 23, and line 46, page 4, for "difficulty" read "difficultly"; page 3, line 119, column 7 of the table, for "10." read "10.5"; and that the said Letters Patent should be read with these corrections therein that the same may conform to the record of the case in the Patent Office.

Signed and sealed this 15th day of August, A. D. 1933.

M. J. Moore.
